US00D779515S

(12) United States Design Patent (10) Patent No.: US D779,515 S
Pierson et al. (45) Date of Patent: * Feb. 21, 2017

(54) DISPLAY SCREEN OR PORTION THEREOF WITH GRAPHICAL USER INTERFACE

(71) Applicant: Shuttersong Incorporated, Wellesley, MA (US)

(72) Inventors: Paul Pierson, New York, NY (US); Kimiyo Nakatsui, New York, NY (US); Nick Spriggs, New York, NY (US)

(73) Assignee: Shuttersong Incorporated, Wellesley, MA (US)

() Term: 14 Years

(21) Appl. No.: 29/502,028

(22) Filed: Sep. 11, 2014

(51) LOC (10) Cl. 14-04

(52) U.S. Cl.

USPC D14/486; D14/488

(57) CLAIM

The ornamental design for a display screen or portion thereof with graphical user interface, as shown and described.

DESCRIPTION

The FIGURE is a front view of a display screen or portion thereof with graphical user interface showing my new design.

The portions of the graphical user interface shown in broken lines form no part of the claimed design.

1 Claim, 1 Drawing Sheet
